(57) **CLAIM**

The ornamental design for a vacuum cleaner suction head as shown and described.

DESCRIPTION

FIG. 1 is a perspective view of a vacuum cleaner suction head showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top view thereof; and,

FIG. 7 is a bottom view thereof.

The dash-dash broken lines appearing in the figures are for the purpose of illustrating portions of the vacuum cleaner suction head that form no part of the claimed design. The dot-dash broken lines define the bounds of the claimed design and form no part thereof.
